H. L. SCHAMBERG

FOOTWEAR

Filed Dec. 4, 1925

Patented Feb. 15, 1927.

UNITED STATES PATENT OFFICE.

HERBERT L. SCHAMBERG, OF NEW YORK, N. Y., ASSIGNOR TO ANNETTE DEUTZ, OF NEW YORK, N. Y.

FOOTWEAR.

Application filed December 4, 1925. Serial No. 73,122.

This invention relates to foot wear, and more particularly is directed to a slipper or shoe of improved construction adapted to be used for bathing and other special purposes.

Among the objects of the invention is the provision of a slipper or shoe of the character described, which shall conform to the natural shape of the wearer's foot, and afford a highly comfortable fit without restricting the free movement of the ankle and toes, and yet be exceedingly cheap to manufacture so as to serve as an inexpensive bathing slipper, neat in appearance, and practical to a high degree for the purposes described.

Other objects of this invention will in part be obvious and in part hereinafter pointed out.

The invention accordingly consists in the features of construction, combinations of elements and arrangement of parts which will be exemplified in the construction hereinafter described, and of which the scope of application will be indicated in the following claims.

In the accompanying drawing, in which is shown one of the various possible illustrative embodiments of this invention,

Figs. 1 and 2 are perspective views of a bathing shoe embodying the invention;

Fig. 3 is a cross-sectional view taken on line 3—3 in Fig. 1; and

Fig. 4 is a plan view of the upper portion of the improved shoe laid flat.

Referring in detail to the drawing, 10 denotes a shoe embodying the invention which is seen to comprise a sole 11 to which an upper 12 is attached in any suitable manner as by means of an inturned seam 13 and stitches 14.

The shoe 10 when used for bathing may have the sole 11 made of two flexible layers, the exterior or under layer 11^a preferably being either of drill, canvas, or other wear-resisting material, and the inner layer 11^b which is adapted to contact with the sole of the wearer's foot being flannelette, or other suitable, soft-surfaced material. The upper 12 may be made in two parts 14 and 15, each preferably of a double-layer construction, the outer layers 14^a and 15^a respectively being either of satin-finished cloth or other suitable material that is neat and attractive in appearance, and the in-

ner layers 14^b and 15^b, respectively, being of any suitable lining fabric.

The two parts 14 and 15 are preferably sewed together by stitches 16 to form the front interfolded seam 17 which extends 60 from the toe end 10^a of the shoe over the top front portion thereof, as shown in Figs. 1 to 3 inclusive.

To facilitate putting on and removing the shoe, the rear upstanding portion of the 65 parts 14 and 15 are provided with suitable releasable closure means, such as a flap 18. The latter may be made as an integral extension of the part 15 or as here shown may be attached to said part 15 in any well 70 known manner.

Quick-detachable fasteners 19 of suitable construction retain the flap 18 in its effective closed position; said fasteners comprising a double row of spaced loop members 19^a provided on the exterior side of the part 14; and a row of rustless, buckle-plates 19^b attached to extend inwardly from the edge portion of the flap 18 and to lie flat thereagainst for retaining said plate in releasable 80 engagement with the loop members 19^a when the plates are inserted into the latter.

It is apparent that the plates 19^b interlock with the loop members 19^a and prevent the releasement of the flap 18 due to tension 85 stress on any parts of the shoe upper 15 tending to pull said flap open, the fasteners 19 being released only when the plates 19^b are withdrawn from the loop members 19^a.

A dominant feature of the invention is the 90 provision of a bathing shoe of simple construction that conforms to the natural shape of the wearer's foot without in any way restricting the free ankle and toe movements while swimming. To this end, as seen from 95 Fig. 4, the parts 14 and 15 forming the upper 12 are shaped substantially dissimilarly, the part 14 being made more pointed and narrower in width at the front portion A, which normally extends over the wearer's 100 big toe than the corresponding portion B of the part 15 which normally extends from the wearer's small toe inward.

It will be understood that the shoe 10 may be constructed of suitable, single layer 105 materials, or if desired, may be made of sheet rubber in any well known manner.

It will thus be seen that there is provided a device in which the several objects of this invention are achieved, and which is well 110

adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

10 Having thus described my invention, I claim as new and desire to secure by Letters Patent:—

15 1. A shoe of the character described comprising a sole, and a two part asymmetrically formed upper formed or flexible material secured thereto and permanently closed at the front of the shoe, said parts of the upper being openable at the back of the shoe to facilitate the putting on and the removal 20 thereof, one of said parts being made from a blank that is shaped more pointed and nar-

rower in width at its front end portion than the other, as and for the purpose described and specified.

2. A shoe of the character described comprising a flexible interlined sole and upper, an inturned seam extending completely around the sole for attaching the interlined upper thereto, said upper being formed of two asymmetrically formed parts, an inter-folded seam connecting said parts together for permanently closing the portion adapted to cover the front of the wearer's foot, said parts being openable at the back of the shoe to facilitate the putting on and removal 35 thereof, one of said parts being made from a blank shaped less pointed and wider at its front end portion than the other, as and for the purpose described and specified.

In testimony whereof I affix my signature.

HERBERT L. SCHAMBERG.
